(57) CLAIM

The ornamental design for a display sign, as shown and described.

DESCRIPTION

FIG. 1 is a front, top, and left side perspective view of a display sign, showing my design;

FIG. 2 is a front elevational view thereof;

FIG. 3 is a right side elevational view thereof;

FIG. 4 is a left side elevational view thereof;

FIG. 5 is a back elevational view thereof;

FIG. 6 is a top plan view thereof; and,

FIG. 7 is a bottom plan view thereof.

The broken lines illustrate portions of the display sign that form no part of the claimed design.
